(57) **CLAIM**

The ornamental design for an electronic shelf label having a lamp hole surface shell as shown and described.

DESCRIPTION

FIG. 1 is a perspective view of a first embodiment of an electronic shelf label having a lamp hole surface shell.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is an enlarged detailed view of portion 8 of FIG. 1.

FIG. 9 is an enlarged view detailed view of portion 9 of FIG. 2.

FIG. 10 is cross-sectional view taken along line 10-10 in FIG. 2.

FIG. 11 is an enlarged detailed view of the portion 11 of FIG. 10.

(Continued)

FIG. 12 is an enlarged back perspective view of the lamp hole surface shell portion, shown isolated for clarity of illustration.

FIG. 13 is a perspective view of a second embodiment of an electronic shelf label having a lamp hole surface shell.

FIG. 14 is a front view of FIG. 13.

FIG. 15 is a rear view of FIG. 13.

FIG. 16 is a left side view of FIG. 13.

FIG. 17 is a right side view of FIG. 13.

FIG. 18 is a top view of FIG. 13.

FIG. 19 is a bottom view of FIG. 13.

FIG. 20 is an enlarged detailed view of portion 20 of FIG. 13.

FIG. 21 is an enlarged view detailed view of portion 21 of FIG. 14.

FIG. 22 is cross-sectional view taken along line 22-22 in FIG. 14; and,

FIG. 23 is an enlarged detailed view of the portion 23 of FIG. 22.

FIG. 24 is an enlarged back perspective view of the lamp hole surface shell portion, shown isolated for clarity of illustration.

The broken line showing of the electronic shelf label having a lamp hole surface shell is for purpose of illustrating portions of the article and forms no part of the claimed design.

1 Claim, 24 Drawing Sheets
